CLAIM

The ornamental design for a rear cover for a utility vehicle, as
shown and described.

DESCRIPTION

FIG. 1 is a perspective view of a rear cover for a utility vehicle
showing our new design;

FIG. 2 is a left side view thereof;

FIG. 3 is a right side view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of the utility vehicle in FIG. 1 and
portions of the rear cover for a utility vehicle in FIGS. 1, and
4-7 are included for the purpose of illustrating environmental
structure and form no part of the claimed design.
